UNITED STATES PATENT OFFICE

WILLIAM A. UTTZ, SR., OF CLEVELAND, OHIO

DESIGN FOR A CASING FOR A TAPE SEALING MACHINE

Application filed July 12, 1929. Serial No. 32,013. Term of patent 14 years.

To all whom it may concern:

Be it known that I, WILLIAM A. UTTZ, Sr., a citizen of the United States, residing at Cleveland, in the county of Cuyahoga and State of Ohio, have invented a new, original, and ornamental Design for a Casing for a Tape Sealing Machine, of which the following is a specification, reference being had to

the accompanying drawing, forming a part thereof, in which the figure is a perspective view of a casing for a tape sealing machine showing my new design.

I claim:

The ornamental design for a casing for a tape sealing machine as shown.

WILLIAM A. UTTZ, SR.
